Primary Examiner — Mitchell I. Siegel*(74) Attorney, Agent, or Firm* — Boudwin Intellectual Property; Daniel Boudwin(57) **CLAIM**

The ornamental design for a pickleball racket grip attachment, as shown and described.

DESCRIPTION

FIG. 1 shows a perspective view of an embodiment of a pickleball racket grip attachment showing my new design. FIG. 2 shows a left-side elevation view of an embodiment of the pickleball racket grip attachment.

FIG. 3 shows a right-side elevation view of an embodiment of the pickleball racket grip attachment.

FIG. 4 shows a front-end elevation view of an embodiment of the pickleball racket grip attachment.

FIG. 5 shows a rear-end elevation view of an embodiment of the pickleball racket grip attachment.

FIG. 6 shows a top plan view of an embodiment of the pickleball racket grip attachment.

FIG. 7 shows a bottom plan view of an embodiment of the pickleball racket grip attachment; and,

FIG. 8 is another perspective view of an embodiment of the pickleball racket grip attachment shown in use on a broken disclosure of a pickleball racket.

The broken lines showing in the drawings represents a pickleball racket that forms no part of the claimed design.
